CLAIM

The ornamental design for a hanger bracket, as shown and described.

DESCRIPTION

FIG. 1 is a front perspective view of the hanger bracket; FIG. 2 is a front elevation view of the hanger bracket, the rear elevation view being a mirror image thereof; FIG. 3 is a left side elevation view thereof; FIG. 4 is right side elevation view thereof; FIG. 5 is a top plan view thereof; FIG. 6 is a bottom plan view thereof; and, FIG. 7 is a front perspective view thereof in use. The broken lines in the drawings show features that form no part of the claimed design. The hanger bracket is shown with a symbolic break in its length. The appearance of any portion of the article between the break lines forms no part of the claimed design.
